UNITED STATES PATENT OFFICE.

CLIFTON HADEN ROBERTS, OF HAZARD, NEBRASKA.

VALVE-LIFTING DEVICE.

1,316,865.

Specification of Letters Patent. Patented Sept. 23, 1919.

Application filed January 13, 1919. Serial No. 270,903.

To all whom it may concern:

Be it known that I, CLIFTON H. ROBERTS, a citizen of the United States, residing at Hazard, in the county of Sherman and State 5 of Nebraska, have invented certain new and useful Improvements in Valve-Lifting Devices, of which the following is a specification.

This invention relates to metal working, 10 and more especially to tools employed in assembling; and the object of the same is to produce an improved valve lifter for use especially on Ford cars.

The invention as a whole is a neat, serv- 15 iceable, and inexpensive tool adapted for ready application and adjustment, and its details of construction are fully set forth in the following specification and claims. In the drawing—

20 Figure 1 is a sectional view through a portion of a cylinder, showing this valve lifter in use.

Fig. 2 is a perspective view of the valve lifter on a larger scale.

25 The well known parts shown in Fig. 1 are the cylinder C and its piston P, the valve whose head is indicated at H and whose stem or rod is lettered R, the coiled spring on the rod lettered S, and the washer W for 30 sustaining the spring. No novelty is claimed for these parts.

The valve lifter best seen in Fig. 2 is by preference constructed as follows: A foot 1 is split at its outer end into two tongues 2, 35 upturned at their extremities into claws 3, and the slot 4 between the tongues is enlarged at 5 to loosely receive the valve rod R between the inner end 6 of the slot and its mouth, the slot at all points being suf- 40 ficiently wide to receive the pin 7 which passes through the rod R beneath the cupped washer W. Therefore, it will be seen that this forked foot may be passed astride the rod directly in line with the pin 7 if de- 45 sired and as shown in Fig. 1, or transversely to the pin, if preferred.

The other end of the foot is bent upward into a channeled arm 10 having its edges turned over into longitudinal guides 11. 50 Slidably mounted along this arm and between its guides is a tongue 12 bent at its upper end at right angles as at 13 so as to stand substantially parallel with the foot. This upper portion 13 is connected with the 55 foot by means of a bolt 14 whose head 15 underlies the foot as seen in Fig. 1, and

whose threaded upper end 16 receives a thumb nut 17 and a washer 18.

Overlying the horizontal upper end 13 of said upper member is a head indicated 60 broadly at 20. Its body is slotted as at 21 and adjustably mounted astride the bolt and over the upper portion 13 and its inner end is cupped upward as at 22 and preferably stamped with a longitudinal rib 23 for the 65 sake of strength. This end of the head overlies the head H of the valve as seen in Fig. 1, while its body overlies the flat portion 13 and may be adjusted beneath the washer 18 as will be clear.

70 The valve lifter is used as shown in Fig. 1. The claws of the foot 1 pass astride the valve rod R under the spring washer W as shown, and the cupped head 22 overlies the head H of the valve as also shown. Now 75 the thumb nut 17 is turned on the threaded end 16 of the bolt to draw the horizontal members of this tool toward each other, as is permitted by the telescoping of the tongue 12 into the guide arm 10, and very soon the 80 spring S is put under tension so that it contracts a little and the foot 1 is lifted off the pin 7. The valve lifter is removed by a reversal of the operation in a manner which 85 will be clear.

The foregoing description and the drawings have reference to what may be considered the preferred form of my invention. It is to be understood, however, that I may make certain changes in construction and arrangement of parts, materials, dimensions, et cetera, as may prove expedient and fall within the scope of the appended claims.

Having thus fully described my invention, what I claim as new and desire to secure by Letters Patent is:—

1. The herein described automobile valve lifter comprising a foot, a head, telescoping elements connecting these members, a bolt standing parallel with said elements and 100 also connecting said members, and a thumb nut on the bolt.

2. A valve lifter comprising a foot forked at its outer end and having its fork-arms upturned into claws, a head slotted longitudinally in its body and having its outer end cupped upward, telescopic connections between these members, and means for drawing the members toward each other, and said means passing through said slot 105 for adjustably holding said head upon one of said connections, as described.

3. A valve lifter comprising a foot forked at its outer end and having its fork-arms upturned into claws, a head slotted longitudinally in its body and having its outer end cupped upward, an arm upstanding rigidly from the inner end of said foot and provided with guides, a tongue depending from beneath the head and slidably mounted in said guides, and means for drawing the head toward the foot, and said means passing through said slot for holding the head in an adjusted position upon said tongue, as described.

4. A valve lifter comprising a foot forked at its outer end and having its fork-arms upturned into claws, a head slotted longitudinally in its body and having its outer end cupped upward, an arm upstanding rigidly from the inner end of said foot and provided with channeled guides along its edges, a tongue slidably mounted in said guides and having its upper end turned at right angles and underlying the head, and a bolt through this head and the upper portion of the tongue and foot and slot of said head, for the purpose set forth.

5. In a valve lifter, the combination with a foot having a slot in its outer end and its inner end upturned and provided with guides, a right angular member having a tongue slidably mounted in said guides and its upper portion paralleling said foot, and a bolt through said upper portion and having a thumb nut; of a head having a slotted body overlying said upper portion and with its slot passing astride said bolt, its inner end being cupped.

6. In a valve lifter, the combination with a foot having its outer end slotted and the

slot enlarged between its extremities to a size to receive the valve rod, and a head having its inner end cupped upward and of a size to receive the valve head; of telescopic elements connecting these members, and means for drawing the members toward each other.

7. In a valve lifter, the combination with a foot having its outer end slotted and the slot enlarged between its extremities to a size to receive the valve rod, and a head having its inner end cupped upward and of a size to receive the valve head; of an arm upstanding from the inner end of the foot, a tongue depending from the head, slidable connections between the tongue and arm, and a bolt through the head and foot and alongside said tongue and arm, for the purpose set forth.

8. In a valve lifter, the combination with a foot, a head, of an arm extending from the inner end of the foot, a tongue depending from the head, slidable connections between the tongue and arms, and a bolt through the head and foot and alongside said tongue and arm, for the purpose set forth.

9. The herein described valve lifter comprising a foot, a head, telescoping elements connecting these members, and means standing parallel with said elements and also connecting said members for drawing the same toward each other, as described.

In testimony whereof I affix my signature in presence of two witnesses.

CLIFTON HADEN ROBERTS.
